VENTILATOR

Filed Oct. 14, 1929

INVENTOR.
DAVID B. BIRD,
BY *H. Woodward*,
ATTORNEY.

UNITED STATES PATENT OFFICE

DAVID B. BIRD, OF CHICAGO, ILLINOIS

VENTILATOR

Application filed October 14, 1929. Serial No. 399,660.

The invention relates to ventilating devices for use when removal of air or gases and their replacement with fresh medium is required. It is a special aim of the invention to present a device for such purposes which is adapted to both remove and introduce air or gases simultaneously. This is of special advantage in certain situations where heretofore it has been a practice to use a blower either to introduce fresh air, or to remove fouled air. In the first instance when fresh air is forced into a chamber such as a kitchen, the displaced air and vapors with attendant odors are apt to be forced into dining or other rooms where patrons will be annoyed; in the second instance, mere removal of undesired air and gases and permitting them to be replaced haphazardly through doors and windows results in admitting undesirable air or vapors in many instances. By the use of my invention a single compact unit is adapted to serve for removal of undesired gases and introduction of air or gases from a preferred source. In ventilating spaces beneath roofs, it is often essential to both expel undesired air and introduce fresh air, for which my invention is especially suitable.

It is an important aim of the invention to present a combined air vent and air supply device which may be incorporated with a simple single flue mounting, involving a minimum of complication both in structural work and extent of labor involved.

A further purpose is to present a novel construction in mounting and flue constructions in such devices. It is also an object to originate a novel and useful control and operating means for such an appliance.

Additional objects, advantages and features of invention reside in the construction, arrangement and combination of parts involved in the embodiment of the invention, as will be understood from the following description, and accompanying drawings; in the latter,

Figure 1 being a vertical sectional view of a portion of roof and a ventilator installed, embodying my invention,

Figure 2 is a horizontal sectional view on the line 2—2 of Figure 1;

Figure 3 is a section on the line 3—3 of Figure 1.

Figure 4 is a horizontal section on the line 4—4 of Fig. 1.

Figure 5 is a fragmentary section on the line 5—5 of Fig. 4.

There is illustrated a portion of a standard roof structure 10, the details of which may vary in different structures or situations. In the present instance there is a sharply inclined deck 11, having supporting rafters 12, between two of which there are inserted cross pieces 13 of similar cross sectional dimension. A suitable opening is cut through the deck between the headers 13, and a top thimble 14 with a flashing flange 15 is secured upon the upper side of the deck around this opening, the thimble including a vertical cylindrical collar portion 16 terminating in a substantially horizontal flange 17. A bottom thimble 18 is secured on the headers 13 and adjacent rafter portions, the bottom thimble having a vertical dependent collar 19 without a flange, and aligned with the collar 16.

Revolute in the two thimbles there is a cylindrical flue 20, provided with a collar 21 at the upper part adapted to lie over the flange 17, the collar having a depending annular flange 22 extending downwardly beside the flange 17 so as to close the space between the two. The flange 17 and the collar 21 where they abut are preferably of uniform undulating form, or corrugated, so that the corrugations of the collar nest with those of the flange 17 and must move across them when the flue is rotated. In this way the weight of the flue tending to hold the corrugated faces in nested relation will prevent casual displacement of the flue from positions to which it may be adjusted by rotation, as will be explained. The flue is formed with a T terminal or head 23 at the upper end, the ends of which are open and flared suitably.

The flue is divided vertically by a septum or partition 23' which may abut or be joined to a horizontal septum 24 diametrically arranged in the T head 22. Affluent and effluent passages 25 and 26 are thus formed. The device may be utilized in this simple form by leaving the bottom of the flue plain and

open on both sides of the septum, and when one end of the T head is presented toward the direction in which a breeze blows, the air may pass freely through the passage in the T head at the upper side of the septum 24, while that entering at the lower side of the septum 24 will be forced downwardly through the flue 20. The flared entrance to the T head will cause a slight compression of air in the passage. This, together with the friction of air moving from the upper side on that immediately below, and by the vacuous condition around the exit end of the T head caused by the air diversion due to the flared sides, will produce an ejector action by which air will be drawn upwardly through the flue to the exit end of the T head and discharged.

Means is illustrated, however, whereby a forced draft may be produced from within through the effluent passages of the flue and T head, with an arrangement whereby the equivalent of the simple flue first described may be produced at any time when desired. This consists in the formation of a closed case or chamber 27 on the lower end of the flue within which is mounted a fan 28 adapted to blow air upwardly, the case being open downwardly and the lower end of the septum 23 being continued laterally to close off the affluent passage 25 from the chamber 27, and a discharge opening 29 is formed through the side of the flue over the case 27.

The opening from the case to the effluent passage is arranged to be closed at will by means of a hinged valve or door 30 pivoted on the septum 23 and inclined upwardly to its swinging edge where it rests against the side of the flue. It is operable by means of a bell crank lever 31 pivoted on the side of the case having an outwardly extended handle positioned conveniently for operation of the lever. A series of slots 32 are formed in the side of the flue communicating only with the effluent passage, and on the flue a shutter 33 is suitably mounted to close the slots by a short movement of the shutter. The shutter is connected by a link 34 with the bell crank lever 31, so that the slots 32 are closed at the same time that the valve 30 is opened.

While the invention has been incorporated in a roof as shown, if desired it may be used in its unit form to be inserted in various openings in buildings or the like, and the non-essential parts in such additional uses may be omitted as discretion indicates. Thus, for use in openings in walls, the cross head or T portion of the flue may be omitted in some cases, and the motor draft utilized without expectation of using the natural draft.

A control for the fan or blower is provided, consisting of a switch 35 including the throw lever 36 movable upwardly to open the switch. The switch may be connected with the motor of the fan and with an elec-

trical source by usual circuits, not shown. As shown, upward movement of the lever 31 will close the shutter 33 and open the valve 30 by reason of connection of these elements with links extending upwardly from the outer part of the lever. The lever is extended inwardly beyond its pivot and this extension 37 connected by a short link 38 to the lever 36. As a result, when the lever is raised to close the shutter and open the valve, the switch to the motor of the fan is also closed and the fan caused to operate.

In both operative positions the handle lever 31 is not far from horizontal position, so that it may also be used readily to rotate the flue and head 23 by horizontal movement of the handle, and full advantage may be taken of wind currents in various directions. In this use, such adjustments of the shutter valve and switch as may have been made will not be disturbed.

I claim:

1. A ventilating appliance comprising a horizontal head having open inlet and outlet flared ends and partitioned to form an open passage therethrough, affluent and effluent ducts communicating with the inlet and outlet ends respectively beside said passage, a blower connected with the inner end of the effluent duct, a valve in the effluent duct, means to operate the valves, a lateral opening from the effluent duct outwardly of the valve, a shutter therefor and means to close the shutter when the valve is open.

2. A ventilator appliance comprising a vertical cylindrical flue having a communicating cross head, affluent and effluent passages formed in the flue, said passages in the flue opening at respective ends of the head, a support for the flue including an annular base member encircling the flue and an opposed relatively revoluble annular member on the flue resting on the base, said annular members having opposed contacting uniformly undulated faces, whereby the weight of the flue opposing the rising of the upper annular member will tend to hold the device in adjusted positions and means to rotate the flue.

3. The structure of claim 1 including a control for the blower, and operative connections common to the control, the valve and the shutter, constructed to place said control in blower-operating position, open the valve and close the shutter at one limit of movement of the operative connections, and place the said control in non-operating position close the valve and open the shutter at another limit of movement.

4. The structure of claim 1 in which said head and ducts are mounted as a unit revoluble on a vertical axis, a control for the blower mounted on the revoluble unit, and operative connections also mounted on the revoluble unit between the said control, the

valve and the shutter, constructed to place the said control in blower-operating position open the valve and close the shutter at one limit of movement of the operative connections, and at another limit of movement to place the said control in non-operating position close the valve and open the shutter, said operating means including means to rotate said unit on said axis.

10 In testimony whereof I affix my signature.
DAVID B. BIRD.
